UNITED STATES PATENT OFFICE.

DAVID H. HUNTER, OF SAN ANTONIO, TEXAS, ASSIGNOR TO SULLIVAN MACHINERY COMPANY, A CORPORATION OF MASSACHUSETTS.

PUMPING SYSTEM.

Application filed July 25, 1919. Serial No. 313,193.

To all whom it may concern:

Be it known that I, DAVID H. HUNTER, a citizen of the United States, residing at San Antonio, in the county of Bexar and State of Texas, have invented certain new and useful Improvements in Pumping Systems, of which the following is a full, clear, and exact specification.

My invention relates to pumping systems.

It has for its object to provide an improved pumping system adapted to supplying widely varying pressures at will, and one, though not being limited thereto, especially adapted to use in pumping wells or the like wherein difficulty is experienced in starting the flow of the pumped fluid.

More particularly, my invention has for its object to provide an improved pumping system whereby a high pressure may be conveniently obtained whenever desired, as when starting the flow from a well, and whereby thereafter, as after the flow has been started, the system is maintained at a lower pressure in an improved manner by a part of the pumping means, the construction being such that while a high pressure is capable of being supplied whenever necessary, the system is normally operated at an economical low pressure. These and other objects and advantages of my improved construction will, however, hereinafter more fully appear.

In the accompanying drawing I have shown for purposes of illustration one embodiment which my invention may assume in practice, illustrating the same as applied to use as a well pump adapted to operate, for example on oil wells, which are notoriously hard to start.

In this illustrative construction I have shown a pumping system including a plurality of compressing units 1 and 2 operatively connected in an improved manner hereinafter described, and, as likewise hereinafter described, adapted to cooperate to supply a high initial starting pressure to an air lift pump 3 disposed in a well casing 4 and discharging into a discharge line 5, or to supply a lower running pressure sufficient to maintain the well flow. In this construction it will further be observed that the unit 1, while it may assume other forms, is illustrated as a multi-stage compressor having a low pressure cylinder 6 and a high pressure cylinder 7 the low pressure cylinder

receiving air from the usual intake 8 and discharging the same into an intercooler 9, which in turn discharges into the high pressure cylinder 7 discharging into a discharge line 10 leading to a receiver 11. Operatively connected to this receiver, herein through piping 12, 13, is the compressor unit 2. While this unit 2 may likewise assume various forms, it is shown herein in the form of a relatively small single stage compressor having a single cylinder 14 receiving the air through the pipe 13 as an inlet and discharging the same through a pipe 15 to a down pipe 16 leading to the air lift pump 3. It will also be observed that I have provided a supplementary pipe connection 17 extending between the receiver and the pump, herein between the pipe 12 and the upper end of the pipe 16, and that I have provided improved controlling mechanism in the several pipe connections, the same herein including a check valve 18 in the pipe connection 17 and a check valve 19 in the pipe connection 15 and throttle valves 20, 21, and 22 in the pipe connections 13, 15, and 17, respectively.

In the operation of my improved construction it will be observed that when it is desired to start the well it is possible to obtain a high pressure by connecting the compressor units in multi-stage relation. More particularly, it will be observed that by opening the pipe connections 13 and 15 and closing the connection 17, the two compressors when started will be caused to operate as a three-stage installation, the air entering through the intake 8 of the unit 1 being compressed thereby through two stages, delivered to the receiver, and from the receiver through the pipe 12 and the pipe connection 13 to the cylinder 14 of the compressor unit 2 where it is compressed through another stage and delivered through the pipe connection 15 and the down pipe 16, to the air lift pump 3. Obviously, this pressure may be maintained as long as necessary, but in well pumping, I find that a continuous high pressure flow is not required for a period longer than the starting period, during which the head is blown off of the well and the normal flow of the latter started. When this occurs, by simply opening the connection 17 and closing the valve 20 to cut off the intake to the compressor unit 2, the latter may be shut down,

while yet leaving a pressure flow from the compressor unit 1 through the pipe connections 12, 17, and 16 to the air lift pump which I have found is sufficient to maintain the desired normal flow from the well. Thus it will be observed that the system may be started with the needed high pressure and thereafter operated economically at the lower pressure developed by the compressor unit 1, herein a multi-stage unit, as soon as the flow from the well is started.

By the use of my improved system, it is possible to start any well which it has heretofore been considered necessary to operate by pumping mechanism continuously supplying thereto a very high pressure, and, instead of continuously supplying said high pressure thereto after the same has been started, operate it at a lower pressure, thereby materially decreasing the cost of the pumping operations. More specifically, with my improved construction it has been found possible to supply a starting pressure of approximately five hundred pounds whenever desired, and after the well has been started continue the normal pumping operation therein at a pressure of one hundred pounds. Further, it will be observed that in my improved construction it is possible thus to start and operate a pumping system without the necessity for providing expensive pumps of special construction supplying abnormal pressure and having only a limited field of use, my improved system instead making it possible to utilize different units each of which is of standard construction and adapted whenever desired to use in other normal and usual relations without changes therein. It will also be noted that the cooperating auxiliary or starting unit is relatively small and adapted to be supplied and connected with its fellow at small expense.

While I have in this application specifically described one embodiment which my invention may assume in practice, it will be understood that this form is shown for purposes of illustration and that the invention may be modified and embodied in various other forms without departing from its spirit or the scope of the appended claims.

What I claim as new and desire to secure by Letters Patent is:

1. An air lift pumping system including pumping means and a compressing mechanism comprising a plurality of cylinders arranged to compress air serially, and means for discharging air from different ones of said series to said pumping means to discharge excess and normal heads, said pumping means being disposed so as to always discharge below the natural liquid level assumed during pumping.

2. An air lift pumping system including pumping means, fluid pressure

means comprising a plurality of cylinders arranged in multi-stage relation, receivers therebetween, and a single means for conducting said fluid from different stages to said pumping means to discharge excess and normal heads, said pumping means being always completely disposed below the natural liquid level which is attained during pumping.

3. In a pumping system, a pumping device, the operation of which is the same at all times during pumping, a plurality of compressor mechanisms connected in multi-stage relation to said pumping device to discharge an excess head, and means for rendering one ineffective and continuing the operation of the other to discharge a normal head.

4. In a pumping system, a pumping device the operation of which is the same at all times during pumping, a plurality of compressor mechanisms connected in multi-stage relation to said pumping device to discharge an excess head, and means for rendering the higher stage mechanism ineffective and continuing the operation of the other to discharge a normal head.

5. In a pumping system, a pumping device, a plurality of compressor mechanisms connected in multi-stage relation to said pumping device to discharge an excess head, and means for by-passing the higher stage mechanism and continuing the operation of the other to discharge a normal head, said pumping device being completely positioned below the natural liquid level which is obtained during pumping.

6. In a pumping system, air lift pumping means, a plurality of cooperating compressor mechanisms discharging thereto for discharging an excess head, and means for cutting out one of said mechanisms at will while continuing the operation of the other to discharge a normal head.

7. In a pumping system, an air lift pump adapted to discharge at substantially a single level, a plurality of cooperating compressor mechanisms connected in multi-stage relation and discharging thereto to discharge an excess head, and means for cutting out one of said mechanisms at will while continuing the operation of the other to discharge a normal head.

8. In a pumping system, an air lift well pump adapted to completely operate below the well level assumed during normal pumping, a starting and running compressor connected in multi-stage relation for discharging an excess head, and means for rendering said starting compressor ineffective after the well flow is started to discharge a normal head.

9. In a pumping system, an air lift well pump, a starting compressor and a running compressor connected in multi-stage rela-

tion for initiating discharge from the well, and mean for by-passing said starting compressor after the well flow is started.

10. In a pumping system, an air lift pump discharging from a single level, a plurality of compressor mechanisms connected in multi-stage relation for initiating discharge from the well, and means for cutting out only the higher stage mechanism of said mechanisms after the pump is started to discharge a normal head.

11. In a pumping system, an air lift pump adapted to be completely operative during pumping and to have air supplied thereto through a single supply means, a multi-stage compressor, a receiver connected thereto, a cooperating compressor connected between said receiver and said pump for increasing the supply pressure to discharge an excess head, and a supplemental connection between said pump and said receiver.

12. In a pumping system, an air lift pump, a plurality of cooperating compressor mechanisms, and means for selectively connecting said mechanisms to said pump in multi-stage relation to increase the supply pressure for discharging an excess head or supplying the discharge of one only thereto for discharging a normal head.

13. In a pumping system, an air lift pump adapted to discharge at only a single level, and means for discharging first an excess head and then a normal head from said level.

14. In a pumping system, an air lift pump adapted to discharge at only a single level, and means for discharging first an excess head and then a normal head from said level and adapted to utilize full pressure at the source of the air supply during discharge of either head.

15. In a pumping system, an air lift pump adapted to discharge at only a single level, and a plurality of means for supplying fluid thereto for discharging first all excess head and then a normal head, said means for discharging the excess head being inoperative during operation of the other means.

16. In a pumping system, for pumping a varying submergence head, an air lift pump adapted to have the same mode of operation during pumping action, a plurality of cooperating compressor mechanisms connected in multi-stage relation, a valved connection between the higher stage mechanism and said pump, a valved connection between said compressors, and a supplementary valved by-pass disposed around said higher stage mechanism.

17. In a pumping system, for pumping a varying submergence head, an air lift pump, a plurality of cooperating compressor

mechanisms connected in multi-stage relation, a valved connection including a check valve between the higher stage mechanism and said pump, a valved connection between said compressors, and a supplementary valved by-pass including a check disposed around said higher stage mechanism.

18. An air lift system having a discharge pump disposed at substantially a single level, compressor mechanism adapted when normally operative to discharge a head from said level, and means whereby said mechanism can discharge another head from said level which is too great to be discharged by the normal operation of said compressor.

19. An air lift system having a discharge pump at substantially a single level, compressor mechanism whose maximum capacity is such as to generate sufficient supply fluid under sufficient pressure to discharge a normal head, and means whereby the pressure of the supply fluid is adapted to be increased beyond said capacity to discharge an excess head.

20. In a pumping system, air lift pumping means, a compressor whose maximum capacity is insufficient to pump an excess head but adapted to pump a normal head, and a second compressor adapted to pump an excess head.

21. In a pumping system, air lift pumping means, and operating means therefor including a compressor whose maximum capacity is insufficient to pump an excess head continuously but adapted to pump a normal head continuously, and a second compressor adapted to pump continuously an excess head.

22. In a pumping system, air lift pumping means having continuously open discharge ports having a fixed relation to the well within which it is disposed, a compressor for discharging an excess head, and a compressor for discharging a normal head but whose maximum capacity is insufficient to pump said excess head.

23. In a pumping system, air lift pumping means, a plurality of compressor cylinders and pistons therein one of which is adapted to generate supply fluid sufficient to discharge a normal head but whose maximum capacity is insufficient to discharge an excess head, the second of said cylinders being adapted to generate a sufficient pressure to discharge said excess head.

24. In an air lift pumping system having pumping means adapted to discharge an excess and normal head from a single level, and a plurality of means for effecting the air supply and adapted to allow discharge of a normal and excess head.

In testimony whereof I affix my signature.
DAVID H. HUNTER.

Certificate of Correction.

It is hereby certified that in Letters Patent No. 1,579,616, granted April 6, 1926, upon the application of David H. Hunter, of San Antonio, Texas, for an improvement in "Pumping Systems," errors appear in the printed specification requiring correction as follows: Page 3, line 45, claim 15, for the word "all" read *an*; line 50, claim 16, after the word "system" strike out the comma, and line 69, claim 17, after the word "check" insert the word *valve*; and that the said Letters Patent should be read with these corrections therein that the same may conform to the record of the case in the Patent Office.

Signed and sealed this 25th day of May, A. D. 1926.

[SEAL.]

WM. A. KINNAN,
Acting Commissioner of Patents.
